(57) CLAIM

The ornamental design for a razor handle, as shown and described herein.

DESCRIPTION

FIG. 1 is a perspective view of a razor handle showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines are included for purposes of illustrating environment and form no part of the claimed design.

1 Claim, 4 Drawing Sheets
